UNITED STATES PATENT OFFICE

CHARLES F. ROPER, OF HOPEDALE, MASSACHUSETTS, ASSIGNOR TO DRAPER COMPANY, OF HOPEDALE, MASSACHUSETTS, A CORPORATION OF MAINE.

FILLING-REPLENISHING LOOM.

SPECIFICATION forming part of Letters Patent No. 726,574, dated April 28, 1903.

Application filed February 5, 1903. Serial No. 141,946. (No model.)

To all whom it may concern:

Be it known that I, CHARLES F. ROPER, a citizen of the United States, and a resident of Hopedale, county of Worcester, State of Massachusetts, have invented an Improvement in Automatic Filling - Replenishing Looms, of which the following description, in connection with the accompanying drawings, is a specification, like letters on the drawings representing like parts.

This invention relates more particularly to looms provided with mechanism for automatically replenishing the filling at the proper time—as, for instance, upon a predetermined exhaustion of the filling in the running shuttle or upon the failure of such filling. A loom of this character to which my invention is applicable forms the subject-matter of United States Patent No. 529,940, dated November 27, 1894. In such looms it sometimes happens that a change of filling is called for at the same time that the shipper is released by or through the operation of the warp stop-motion or the protector mechanism—i. e., upon the occurrence of a warp or a shuttle fault. When this occurs, the loom is slowing down, and the momentum of the lay is not always sufficient to complete the filling replenishment by driving the filling-carrier or bobbin into proper engagement with the holding device therefor in the shuttle. On starting up the loom again it is possible for the weaver to put everything in normal position, so that the loom will start with the filling-carrier loose in the shuttle, and hence liable to be thrown out, thereby causing damage of various kinds. So, too, when the loom is equipped with an “antibang” device and the loom “knocks off” with the shuttle in the shed a filling-carrier is certain to be thrown out of the hopper or filling-feeder by or through the action of the filling-fork if the loom turns over a sufficient number of times. This of course makes one more filling-carrier to be put into the hopper by the weaver, and it may also cause trouble by having the filling-carrier which is thrown from the hopper catch in the picker-slot or in the shuttle-box to be struck later by the shuttle.

In my present invention I have provided means to prevent the operation of the filling-

replenishing mechanism if the shipper has been thrown off or released from its running position.

The various novel features of my invention will be fully described in the subjoined specification and particularly pointed out in the following claims.

Figure 1 is a top or plan view of a portion of a loom at the shipper side thereof with one embodiment of my invention applied thereto. Fig. 2 is a left-hand side elevation of the apparatus shown in Fig. 1, a portion of the hopper of the replenishing mechanism being shown, the knock-off lever for the shipper being cut off on the line 22, Fig. 1. Fig. 3 is a right-hand side elevation of the dog, to be referred to, shown in Figs. 1 and 2, and Fig. 4 is a perspective detail of the dog to more clearly illustrate its construction.

Referring to Figs. 1 and 2, the breast-beam A⁴⁰, the notched holding-plate N for the shipper S, the controlling or operating rock-shaft d', by or through which the time of operation of the replenishing mechanism is governed, the stand b⁸, the filling detector or fork b¹², and its slide b⁹, longitudinally movable in the stand by or through the weft-hammer W, Fig. 1, may be and are all substantially as in said Patent No. 529,940, the stand a⁷ supporting the hopper or filling-feeder.

In Fig. 2 I have shown a frog F, mounted on the loom side A, the frog having a projection f¹⁰ to engage the lower end of a knock-off lever f¹² when the frog is moved forward by or through the operation of protector mechanism of usual character. This “protector knock-off lever” f¹², as it may be termed, is fulcrumed at f¹³ on the loom side, its upper end being bent at f¹⁴ in front of the shipper, so that when the lever is rocked in the direction of arrow 15 the shipper will be released from its holding-notch to effect the stoppage of the loom in well-known manner. A second knock-off lever k is fulcrumed at k^x on the breast-beam adjacent the holding-plate N, the outer end of said lever extending in front of the shipper, as shown in Fig. 1, the inner end of the lever having an enlargement k' thereon in front of a latch d⁵ on the filling-fork slide b⁹. This latch operates upon two successive outward movements of the

slide, substantially as provided for in United States Patent No. 529,943, to engage the enlargement k' and move the lever k to release the shipper and stop the loom with a filling-carrier in the shuttle. A link k^2 is pivotally connected at its front end with the knock-off lever k , and at its rear end it is connected with the upturned end k^3 of a lever k^4 , fulcrumed at k^5 on the loom side, (see Fig. 2,) 5 a spring s^x acting upon said lever to normally keep the outer end of the knock-off lever k pressed against the shipper. When the shipper is released by the protector knock-off lever f^{12} , the spring acts through link k^2 to 10 swing the lever k on its fulcrum in the direction of arrow 20, Fig. 1, for a purpose to be described, the release of the shipper manifestly permitting the spring to act. The slide 15 b^9 has an overhanging part b^4 , terminating in a transverse shoulder b^7 , and a forward extension b^6 on a lower plane, the extension engaging a spring s^2 , Fig. 2, mounted on the loom-frame, the spring moving the slide rearwardly after it has been moved outward by 20 or through detection of filling failure. An upturned arm d^2 , fast on the rock-shaft d' , has its upper end turned over at d^3 , above the extension b^6 , and a stop-lug d^4 is formed on the outer face of the arm. The latter has 25 fulcrumed upon it on a lateral pin d^x a peculiarly-shaped dog e , said dog being broadened on one side to form an overhanging shoulder e^x , (see Figs. 3 and 4,) the rear edge of the shoulder presenting a face e' , while 30 the rear edge of the dog presents a beveled face e^2 . A rearwardly-projecting tail e^3 on the dog extends from the shoulder over and normally rests upon the part b^4 of the fork-slide, and the enlargement k' under normal 35 conditions occupies the position shown in Fig. 2 beneath the part b^4 and back of and adjacent the face e^2 of the dog, while the shoulder b^7 is behind and adjacent the face e' . If the slide b^9 is moved outward, as upon detection 40 of filling failure, the shoulder b^7 immediately engages the face e' of the dog, moves the latter outward, and thereby swings the arm d^2 out to turn the rock-shaft d' far enough to effect the operation of the replenishing mechanism. If the protector mechanism 45 operates, moving the frog F forward, the knock-off lever f^{12} will be turned to release the shipper from its holding-notch, and the spring s^x then moves the enlargement k' forward to engage the inclined face e^2 of the dog. This acts to swing the dog up on its fulcrum 50 d^x into dotted-line position, Fig. 3, and thereby the shoulder e^x and its face e' is lifted above the part b^4 , so that should the slide be moved outward the shoulder b^7 could not engage the face e' and the dog would not be moved. So long as the shipper is thrown off 55 or in stopping position the outward movement of the slide b^9 cannot act upon the dog, and the replenishing mechanism cannot operate, even though the shuttle may have stopped in the shed, and the fork detects ab-

sence of filling, for the enlargement k' keeps the dog in inoperative position. Such outward movement of the slide, however, will cause the shoulder b^7 to engage the inturned end d^8 of arm d^2 , and thereby turn the rock-shaft d' far enough to arrest take-up, substantially as provided for in United States Patent No. 711,730, dated October 21, 1902. 70 A stop-lug e^4 on the dog engages the lug d^4 when the dog is thus rocked or tilted to prevent undue movement of the dog. If the slide b^9 is given a plurality of successive outward movements—as, for instance, if the first 75 change of filling fails to properly thread in the shuttle—then the latch d^5 drops behind the enlargement k' and the knock-off lever k is turned to release the shipper on the next outward movement of the slide. At such time, 80 however, the shoulder b^7 of the slide will engage the dog before the latter can be rendered inoperative by or through the enlargement k' , and as a result the second movement of the slide puts a filling-carrier in the shuttle 85 substantially simultaneously with the release of the shipper. The lever k^4 is arranged to operate when a warp failure occurs—as, for instance, in United States Patent No. 623,174—and when the upper end of the lever 90 is swung forward the link k^2 will swing the knock-off lever k , and thereby release the shipper. At such time the enlargement k' will act as before described to render the dog e inoperative, so that the operation of the replenishing mechanism cannot be effected, even though the slide b^9 is moved outward. 95 It will be manifest, therefore, that whenever the shipper is released, whether by the action of the protector mechanism or upon the occurrence of a warp failure, the replenishing mechanism will be rendered inoperative while the shipper is in stopping position. Even if the shipper is released by the weaver the said mechanism cannot operate, for the part k' will, 100 through the spring s^x , render the dog e inoperative or irresponsible to an outward movement of the fork-slide, as before described. 105

When the shipper is moved to running position, it engages the beveled end k^5 of the knock-off lever k , Fig. 1, and restores the latter to the position shown in Figs. 1 and 2, and thereby the enlargement k' is withdrawn from the dog, permitting the latter to return to normal position. The spring s^x is merely 115 strong enough to cause the knock-off lever k to follow the shipper when released from its holding-notch.

The failure of the shuttle to be properly positioned in the shuttle-box causes the operation of the protector mechanism and for the purposes of this invention is termed a “shuttle fault,” while failure or breakage of the warp is termed a “warp fault.”

The shipper is released from its holding-notch by or through the knock-off lever k , whether the warp or filling fails, as has been pointed out, while the protector mechanism acts upon the occurrence of a shuttle fault 130

to release the shipper through the knock-off lever f^{12} .

The controlling rock-shaft d' and the dog e carried thereby form part of the means for controlling the time of operation of the filling-replenishing mechanism, and the dog is rendered inoperative through the instrumentality of the enlargement k' upon the occurrence of a fault in the warp or improper positioning of the shuttle, the shipper when released permitting the enlargement to be operatively moved at such time by another agency.

The member which throws the power on or off from the loom, shown herein as a shipper, constitutes a device to govern the operation of the loom, such device moving into position to stop the loom when released from the notch in the usual holding-plate, the return of the governing device to the notch effecting the starting of the loom.

My invention is not restricted to the precise construction herein shown and described, as the same may be modified or rearranged in various particulars without departing from the spirit and scope of my invention.

Having fully described my invention, what I claim as new, and desire to secure by Letters Patent, is—

30 1. In a loom, a device to govern its operation, automatic filling-replenishing mechanism, and means actuated automatically and independently of said device to prevent the operation of the replenishing mechanism, 35 when said device is in position to effect stoppage of the loom.

2. In a loom, a device to govern its operation, automatic filling-replenishing mechanism, means to prevent the operation thereof, 40 maintained inactive by the governing device when the latter is in running position, and an actuator for said means, independent of the governing device, the actuator causing said means to operate when the governing device moves to position to effect stoppage of the loom.

3. In a loom, a device to govern its operation, automatic filling-replenishing mechanism, means to prevent the operation thereof, 50 when said governing device is in position to effect the stoppage of the loom, and an actuator operative by or through the occurrence of a warp or shuttle fault to render said means operative.

55 4. In a loom, a shipper, automatic filling-replenishing mechanism, means to prevent the operation thereof, said means being main-

tained inoperative by the shipper when in running position, and an actuator independent of the shipper to render said means operative 60 upon movement of the shipper to stopping position.

5. In a loom, a shipper, automatic filling-replenishing mechanism, normally inactive means to prevent the operation thereof, and 65 an instrumentality independent of the shipper and operative by or through the occurrence of an abnormal condition in the warp or shuttle to render said means active to prevent operation of the replenishing mechanism 70 when the shipper is in stopping position.

6. In a loom, a shipper, automatic filling-replenishing mechanism, means, maintained inactive by the shipper when in running position, to prevent the operation of the replenishing mechanism, means to effect the release of the shipper by or through the occurrence of a warp or shuttle fault, and an instrumentality operative upon the occurrence of such fault to render said means active to prevent 80 operation of the replenishing mechanism when the shipper is in stopping position.

7. In a loom, filling-replenishing mechanism, and means to control the time of operation thereof, including a controlling-shaft and 85 a pivotally-mounted dog carried thereby, a filling-fork, and a slide adapted to engage the dog and rock said shaft upon detection of filling failure, combined with a shipper, means to release it, and a device operative automatically upon release of the shipper to move the dog out of the path of the slide and maintain it in such position while the shipper is in stopping position.

8. In a loom, filling-replenishing mechanism, and means to control the time of operation thereof, including a controlling-shaft and a normally operative dog carried thereby, combined with a shipper, means to release it upon the occurrence of a warp or shuttle fault, 100 and a device operated independently of the shipper upon release thereof to coöperate with and render the dog inoperative while the shipper is in stopping position, to thereby prevent the operation of the replenishing mechanism 105 at such time.

In testimony whereof I have signed my name to this specification in the presence of two subscribing witnesses.
